Patented Feb. 3, 1976

238,669

ELECTRIC PENCIL SHARPENER

Francis W. MacGregor, New Britain, Conn., assignor to
Hunt Manufacturing Co., Philadelphia, Pa.

Filed Oct. 29, 1973, Ser. No. 410,628

Term of patent 14 years

Int. Cl. D19—06

U.S. Cl. D19—73

FIG. 1.

FIG. 2.

FIG. 3

FIG. 4.

FIG. 5.

FIG. 6.

FIG. 1 is a front elevational view of an electric pencil sharpener showing my new design;

FIG. 2 is a rear elevational view;

FIG. 3 is a top plan view;

FIG. 4 is a bottom plan view;

FIG. 5 is a right side elevational view; and

FIG. 6 is a left side elevational view.

I claim:

The ornamental design for an electric pencil sharpener, as shown and described.
